(57) **CLAIM**

The ornamental design for a guitar tremolo, as shown and described.

DESCRIPTION

FIG. 1 is a perspective view of a guitar tremolo showing our new design;

FIG. 2 is a right side elevational view thereof; and,

FIG. 3 is a top plan view thereof.

The left side elevational view is a mirror image of the right side elevational view, and is not illustrated. The bottom plan view is not illustrated as it forms not part of the present invention.

The rear elevational view is not illustrated as it forms no part of the claimed design. The broken lines are for illustrative purposes only and form no part of the claimed design.
